PROCESS FOR PRODUCING OILS WITH LOW POUR POINTS

Bruno Engel, Appelviken, Sweden, assignor to Aktiebolaget Separator-Nobel, Stockholm, Sweden, a corporation of Sweden

Application December 31, 1938, Serial No. 248,874
In Germany January 4, 1938

8 Claims. (Cl. 196—18)

In the dewaxing of oils and tars as well as their distillation and transformation products it is generally desirable that the dewaxed oil should have as low a pour point and as flat a temperature-viscosity curve as possible. In order to remove the wax from the said products, they are diluted by adding a greater or lesser amount of a solvent and are then chilled, whereupon the solid wax precipitated at the low temperature is removed by means of filters, presses, centrifuges or the like.

In such processes the refrigerating energy required for the chilling is of great economic importance. It is therefore desirable to use as small an amount as possible of such solvents by which is obtained an oil whose pour point is scarcely higher than the dewaxing temperature. This requirement is fulfilled only by solvents of the type which have a marked selectivity relative to the groups of hydrocarbons contained in the oils, such as paraffinic and naphthenic and aromatic compounds.

The greater the selectivity of the solvent, the higher the temperature which may be used for the removal of a given amount of solid wax and for obtaining a given pour point. On the other hand, if a solvent without selective effect is used, the dewaxing must be effected at a comparatively low temperature if the same pour point is to be secured.

For instance, to produce an oil having a pour point of -15° C. from a Roumanian mineral oil distillate by means of dewaxing, it is necessary to cool to at least -40° C. if non-selective solvents, such as propane, butane or naphtha, are used, while a temperature of only -15° to -17° C. is sufficient if a selective solvent, such as dichloroethane, is used. In the latter case the amount of solvent required is also substantially smaller than in the former.

If paraffin base oils are treated, the selective qualities of the solvents have, of course, practically no disadvantageous effect on the viscosity-temperature curve. But with mixed base oils, and to a still higher degree with asphalt base oils, the selectivity may cause disadvantages, as the highly polymeric hydrocarbons, such as resins, asphalts, etc., are precipitated in more or less colloidal form and make the removal of the wax more difficult, the yield thereby often being considerably reduced. In order to avoid this, aromatic hydrocarbons, such as benzene, toluene, are in many cases added as so-called "oil-dissolving agents" to the ordinary dewaxing agents.

As a further disadvantageous phenomenon, it

may be mentioned that besides the solid wax precipitated at the given temperature, valuable paraffin hydrocarbons, which are liquid at ordinary temperature, are precipitated or enclosed in the solid phase, which entails not only a reduction in yield of oil but also a very considerable reduction of the viscosity index of the dewaxed oil.

This phenomenon, which is particularly conspicuous in connection with mixed base oils, may make it impossible to obtain a given low pour point with the aid of selective dewaxing agents. If, for instance, it is desirable to obtain a pour point of -20° C., it would be necessary to treat the oil with a suitable wax precipitating agent at a temperature between -15° and -20° C. Within this temperature range and with the kinds of oils mentioned above, the selectivity is so high that a considerable proportion of the valuable paraffin lubricating oil constituents are enclosed in the precipitated solid wax, with a resultant reduction not only in yield but also in the viscosity index. If, on the other hand, the dewaxing is carried out at a comparatively high temperature, for instance above -15° C., the solubility of the crystalline wax is too high, and the oils obtained have a pour point considerably higher than that required.

It has now been found that these objections can be avoided by effecting the dewaxing with the aid of selective wax precipitating agents in two or more stages. A selective separation of the solid and fluid wax particles from the other groups of hydrocarbons is first effected. Then a separation at higher temperature of the mixture of wax hydrocarbons into solid crystalline wax and fluid lubricating oil particles is effected. Finally, the fluid paraffin hydrocarbons obtained in the second separation are, all or partly, added to the primary oil (hereinafter called "extract") obtained in the first separation.

By this process the following advantages are obtained:

1. Only the solid hydrocarbons, which increase the pour point of the oil, are separated as the final wax product. They are obtained in very pure form.
2. By adding the fluid wax hydrocarbons to the primary oil, not only lubricating oils with a "paraffin" pour point, but also lubricants with a flat viscosity-temperature curve, are obtained.
3. It is allowable to keep in solution or to bring into solution a relatively great proportion of the soft wax, possibly all the soft waxes, which, as is well known, substantially raise the viscosity in-

dex, without substantially raising the pour point.

If the first separating stage is carried out at a comparatively low temperature, the obtained "extract" is a concentrate of viscosity bearers rich in aromatics, which renders difficult the precipitation of soft wax, etc., in the same manner as takes place on addition of so-called pour point reducers. Consequently the second separating stage, that is, the division into solid wax and paraffinic lubricating oil components, can be carried out at comparatively high temperatures. By mixing the "extract" from the first stage with the fluid hydrocarbons liberated from the hard wax, the pour point of the hydrocarbons is substantially lowered, and simultaneously the viscosity index of the dewaxed primary oil or extract and the total yield of oil are considerably raised.

This process is advantageously carried out in continuous operation in centrifuges, as indicated in the following example.

100 kg. of a Roumanian heavy distillate are mixed with 200 kg. dichlorethane and centrifuged at -20° C. Thereby are obtained 64 kg. mixture of dewaxed oil and solvent as well as 236 kg. mixture of solid wax hydrocarbons and enclosed therein fluid wax hydrocarbons with solvent. From 64 kg. dewaxed oil and solvent, 14 kg. "extract" are obtained by distillation. The 236 kg. wax and solvent are now heated under stirring to from 0 to $+5^{\circ}$ C. and are again subjected to continuous centrifugation. There are thereby obtained 80 kg. petrolatum consisting of 38 kg. hard wax and 42 kg. dichlorethane, as well as 156 kg. mixture of fluid wax hydrocarbons containing 108 kg. dichlorethane and 48 kg. oil. The latter is mixed with the originally obtained 14 kg. "extract." As a final product there are obtained a total of 62% oil with a pour point of -20° C. and a viscosity index of 86, and 38% wax having a melting point of 66° C.

In the drawing, which is a diagrammatic view of an apparatus for carrying out the above described example process: *a* is a tank for blending the distillate with the selective solvent; *b*, *c*, *c*, chillers; *d* a centrifugal separator in which is separated the primary dewaxed oil dissolved in a minor proportion of the solvent from the mixture of solid and fluid hydrocarbons (the primary wax) and the bulk of the solvent; *e* a still for distilling off the solvent (which is returned to the solvent storage tank *f* through line *g*) from the "extract"; *h* a heat exchanger wherein the temperature of the diluted primary wax is raised, usually from 20 to 25° C., to obtain a mixture of solid crystalline wax and a solution of fluid wax hydrocarbons and solvent; *i* the centrifuge in which the solid crystalline wax and some of the solvent are separated from the solution of fluid paraffinic oil and the remainder of the solvent; *k* the still in which the solvent is separated from the said paraffinic oil; *m* the still in which the solvent is separated from the hard wax; *n* the return line for distilled solvent from still *k* to the solvent storage tank—conveniently through line *g*; *o* the return line for distilled solvent from still *m* to the solvent storage tank; and *p* a line through which a small proportion of the non-paraffinic oil may be added to the oil to be dewaxed prior to chilling, as herein-after described.

If the process is carried out in only one stage with the same quantity of the same solvent at for instance $+5^{\circ}$ C., the major portion of the valuable viscosity bearers, that is, those substances

which according to the method above described are obtained as "extract" in the first stage, remain in the said petrolatum owing to the unsatisfactory selectivity at the temperature indicated. In this way not only a wax of inferior quality is obtained but also a reduced yield of low quality oil having a pour point of $+5^{\circ}$ C. due to lack of extract substances by which the pour point is lowered.

10 It is true that it is possible to obtain a sufficient concentration of "extract" substances in the dewaxed oil to ensure the desired pour point by substantially increasing the amount of solvent, using in this case, for instance, a tenfold quantity, 15 which can also be deduced by means of the laws of the solubility. However, the use of large amounts of solvent not only entails considerable economic disadvantages owing to the high refrigerating and distilling energy utilized for the solvent, but a considerable dissolution of solid wax hydrocarbons also results, which in turn raises the pour point of the oil considerably.

The selective effect of the dewaxing agents herein considered may also be utilized for obtaining substances which have the same qualities as the so-called pour point reducers sold in the open market. It has been found, in connection with the dewaxing of (particularly) mixed base oils or distillates with, for instance, dichloroethane, dichlorethylene, methylenechloride, trichlorethane, and less desirably, tetrachlorethylene and carbontetrachloride, and with mixtures of the same with ketones, alcohols, ethers, esters, etc. at low temperatures, for instance, below 35 -20° C., that "extracts" are obtained of which small amounts suffice to reduce the pour point of oils 10 to 20 or more degrees, without having any practically unfavorable influence on the viscosity index.

40 The lower the separating temperature used for obtaining the natural pour point reducer, the lower the yield, but also the higher the concentration and consequently the effect.

If, for instance, a Roumanian overhead distillate is treated with the same volume of dichlorethane at -30° C., about 15% "extract" of high viscosity is obtained. If now only 3% "extract" is added to a gas oil having a pour point of $+6^{\circ}$ C. and a viscosity of 1.82° E. at 20° C. and a viscosity index of 90, the pour point of the gas oil is lowered to -12° C., without changing the viscosity index. If the same treatment of the overhead is carried out at -40° C., it is true that only about 10% "extract" is obtained, but to obtain the low pour point referred to above with the same gas oil it is now necessary to add only 1%. With increasing amounts of "extract" the pour point is, of course, further lowered.

60 The amount of natural pour point reducer to be added is generally so small that a harmful influence on the color of the oils treated therewith need not be feared. If necessary, the pour point reducer may be made lighter in color by chemical or physical refining, for instance, with fullers earth in benzine solution or the like.

While the natural pour point reducers thus obtained have the same effect in regard to the lowering of the pour point and the maintenance of the viscosity index as the artificial ones which 70 may be obtained, for instance, by condensation of naphthalene, anthracene, etc., with chlorinated wax according to the method Friedl-Crafts, they offer the following considerable advantages over the latter products.

1. They are natural products and therefore it

is in many cases unnecessary to add a foreign oil to a given oil.

2. Their production is not dependent on special chemical and expensive reaction processes.

3. They can be obtained in more or less high concentration by using suitable selective solvents in connection with several dewaxing processes, and can then be added to a paraffinic oil as pour point reducer. Possibly they can be obtained in comparatively low concentration at the stage dewaxing according to the method described above; and after the division of the wax hydrocarbons into solid and fluid particles, they can again be added to the latter.

4. While the artificial pour point reducers hardly influence the cloud point, the natural reducers cause a lowering of the same.

The natural pour point reducers may also be obtained by first liberating the oil at low temperature with the aid of a non-selective solvent from the crystalline hard wax, whereupon the treatment with the selective agent is effected.

The natural pour point reducers produced according to the process described above may be added to the oils to be dewaxed also prior to the chilling to low temperature or the removal of the wax, respectively, in order to obtain a better crystallization of wax and to increase the yield of oil.

A solvent or a combination of solvents according to the preceding description is the more "selective" the better it dissolves the naphthenic and/or aromatic compounds on one hand and the less it dissolves the paraffinic compounds on the other hand; naphtha, propane and similar light hydrocarbon oil fractions are not "selective" solvents, as their temperature-solubility-curves for paraffinic compounds do not essentially differ from their temperature-solubility-curves for non-paraffinic compounds. The following solvents may be mentioned as examples of selective solvents: chlorinated hydrocarbons, alcohols, ketones, aldehydes, esters and the like, separate or in mixtures, but of course the method is not restricted to the use of these solvents and mixtures. However, it is to be understood that by a "selective" solvent is meant to include only those solvents whose temperature-solubility curve for paraffinic compounds differs so substantially from their temperature-solubility curve for non-paraffinic compounds that they are relatively good solvents for the naphthenic and/or aromatic compounds and relatively poor solvents for the paraffinic compounds. Of such solvents, those whose sole or main constituent is a chlorinated hydrocarbon, of which a number of examples are hereinbefore given, offer distinct advantages.

What I claim and desire to protect by Letters Patent is:

1. The process of treating wax-bearing hydrocarbon oils to obtain therefrom oils having low pour points and good viscosity-temperature characteristics, which comprises adding to the oil a solvent selective non-paraffinic hydrocarbon and cooling to a temperature adapted to precipitate solid wax and fluid paraffinic hydrocarbons and centrifugally separating the same with a major proportion of the solvent from the oil and a minor proportion of the solvent to thereby produce a solution of a non-paraffinic low pour-point, low cloud-point-reducing extract and a minor proportion of the solvent, and subsequently substantially raising the temperature of the mixture of solid wax paraffinic hydrocar-

bons and solvent to form a mixture of solid crystalline wax and a solution of solvent and paraffinic oil and at that temperature separating the last named solution, containing the major part of the solvent of said mixture, from the said solid crystalline wax and such minor part of the solvent as is carried off with the wax.

2. The process set forth in claim 1 in which substantially all the solvent present in the second specified separating step is that which is added thereto preparatory to the first specified separating step.

3. The process set forth in claim 1 in which the said selective solvent comprises a chlorinated hydrocarbon.

4. The process set forth in claim 1 in which the temperature to which the solution is chilled preparatory to the specified centrifugal separation is not substantially above -15° C. and in which the temperature to which the mixture of solid wax, paraffinic hydrocarbons and solvent separated in the said centrifugal separation is heated preparatory to the second specified separation is not substantially less than 20° C. above the temperature to which it was chilled preparatory to the first specified separation.

5. The process set forth in claim 1 in which the temperature to which the solution is chilled preparatory to the specified centrifugal separation is not substantially above -15° C. and in which the temperature to which the mixture of solid wax, paraffinic hydrocarbons and solvent separated in the said centrifugal separation is heated preparatory to the second specified separation is approximately 20-25° C. above the temperature to which it was chilled preparatory to the first specified separation.

6. The process of treating wax-bearing hydrocarbon oils to obtain therefrom oils having low pour points and good viscosity-temperature characteristics, which comprises adding to the oil a solvent selective for non-paraffinic hydrocarbons and cooling to a temperature adapted to precipitate solid wax and fluid paraffinic hydrocarbons and centrifugally separating the same with a major proportion of the solvent from the oil and a minor proportion of the solvent to thereby produce a solution of a non-paraffinic low pour-point, low cloud-point-reducing extract

40 and a minor proportion of the solvent, subsequently substantially raising the temperature of the mixture of solid wax paraffinic hydrocarbons and solvent to form a mixture of solid crystalline wax and a solution of solvent and paraffinic oil and at that temperature separating the last named solution, containing the major part of the solvent of said mixture, from the said solid crystalline wax and such minor part of the solvent as is carried off with the wax, and adding said non-paraffinic extract in small proportions to

45 said wax-bearing starting oil to thereby obtain a better crystallization of wax and increase the yield of oil.

7. The process of treating wax-bearing hydrocarbon oil to obtain therefrom oils having low pour points and good viscosity-temperature characteristics, which comprises adding to the wax-bearing hydrocarbon oil a solvent selective for non-paraffinic hydrocarbons and cooling to a temperature adapted to precipitate solid wax enclosing therein fluid paraffinic hydrocarbons and subjecting the same to such centrifugal operation as to separately discharge two constituents, namely, a constituent which consists of a solution of oil and solvent containing such minor

proportion of the solvent that the oil in the solution is a non-paraffinic low pour-point, low cloud-point-reducing extract and a constituent which is a mixture of said solid wax and a solution comprising the remaining major proportion of the solvent and an oil which is a fluid mainly paraffinic oil, and subsequently substantially raising the temperature of said mixture to render a part of said solid wax fluid to thereby form a mixture of solid crystalline wax and a solution of solvent and oil which is mainly paraffinic and

at that temperature separating the last named solution, containing the major part of the solvent, from the solid crystalline wax and such minor part of the solvent as is retained with the wax.

5. The process set forth in claim 7, followed by separation of said extract and said fluid mainly paraffinic oil from their respective solvents and mixing said extract and oil to thereby obtain the desired product.
